US00D492479S1

(12) United States Design Patent (10) Patent No.: US D492,479 S
(45) Date of Patent: * Jul. 6, 2004

(54) HANDBAG

(75) Inventor: Raphaëlle Hanley, Paris (FR)

(73) Assignee: Louis Vuitton Malletier, Paris (FR)

() Term: 14 Years

(21) Appl. No.: 29/191,448

(22) Filed: Oct. 7, 2003

(51) LOC (7) Cl. 03-01

(52) U.S. Cl. D3/243

(58) Field of Search D3/232, 233, 239, D3/240, 241, 243, 245, 246, 303, D9/305; 150/100, 107, 108, 110, 111, 114; 190/16, 19, 100, 103, 104, 106, 112, 115, 116, 119, 121, 900, 901, 902, 903; 383/86, 98, 99, 104, 105, 119, 120, 121.1, 127
